CIGARETTE DISPENSER OR SIMILAR ARTICLE

Robert E. Johnson, Duluth, Minn.

Application October 28, 1949, Serial No. 5,747

Term of patent 7 years

(Cl. D52—2)

To all whom it may concern:

Be it known that I, Robert E. Johnson, a citizen of the United States of America, residing at Duluth, in the county of St. Louis and State of Minnesota, have invented a new, original, and ornamental Design for a Cigarette Dispenser or Similar Article, of which the following is a specification, reference being had to the accompanying drawing, forming a part thereof:

In the drawing:

Fig. 1 is a perspective view of a cigarette dispenser showing my new design.

Fig. 2 is a perspective view showing the rear view of my cigarette dispenser.

Fig. 3 is a perspective view showing my cigarette dispenser from a low angle.

I claim:

The ornamental design for a cigarette dispenser or similar article, substantially as shown.

ROBERT E. JOHNSON.
